UNITED STATES PATENT OFFICE

2,532,706

ADJUSTABLE LAVATORY FOR
ARTICULATED BEDS

Robert R. Freund, Mount Carmel, Ill.

Application October 11, 1946, Serial No. 702,841

5 Claims. (Cl. 5—92)

1

This invention relates to an articulated chair or bed structure suitable for invalid or hospital use and is a continuation-in-part of the copending application Serial No. 548,981, filed August 11, 1944, now Patent No. 2,498,736, granted February 28, 1950, and entitled Lavatory and Like Articulated Bed.

The chief object of the present invention is to provide such a bed structure with a fixture capable of multiple use and capable of use in a plurality of positions, depending upon the desired use and the bed section positioning, or capable of being positioned entirely out of the way whenever desired or required.

One chief feature of the invention resides in pivotally supporting a lavatory or like device upon a pivotally mounted back section of a structure recited above and for movement therewith and movement relative thereto and through power means controllable by the bed occupant or patient.

Another chief feature of the invention resides in providing upon a tiltable back section a head section and said sections being capable of conjoint movement, the head section also being capable of independent movement, the aforesaid sanitary device being suitably mounted with respect to both sections.

Still a further feature of the invention resides in the adjustable mounting of the fixture upon its immediate supports so that it may function as a reading or writing desk, among other uses.

Still another feature of the invention resides in means for locking the device with respect to its immediate supports in the relative adjusted tilted position.

A still further feature of the invention resides in limiting the adjustment or tilting of the aforesaid immediate supports in their tilting movement upon the tiltable back section.

Other objects and features of the invention will be set forth more fully hereinafter.

The full nature of the invention will be understood from the accompanying drawings and the following description and claims:

In the drawings Fig. 1 is a perspective view of a portion of an articulated bed structure with sections disposed in chair position and including a tiltable head rest and a sanitary device, the sanitary device being disposed forwardly for toilet and make-up purposes.

Fig. 2 is a perspective view of the same parts with sanitary device disposed overhead.

Fig. 3 is a substantially front elevation of the sanitary device and a waste connection for drainage purposes.

Fig. 4 is an enlarged sectional view of the travel limit means associated with the pivotal connection between the back section and the sanitary device supporting arms.

2

In Fig. 1 of the drawings 10 indicates in general a frame which is of bed width and of a length appreciably less than bed length. At one end of the frame, near the upper portion thereof and within the confines thereof, there is pivoted a back section 11. Thereon near the opposite end of the back section there is pivoted at 12 a head rest section 13, and suitable power means carried by the back rest section is connected to the head rest section for adjusting the relative position of the head section relative to the back section, such adjustment being from approximately 15° rearwardly or downwardly of the back section to 45° forwardly or upwardly of the back section, reference being had to the general plane thereof when vertical or horizontal respectively.

With the back section substantially horizontally disposed, the head section, when titled upwardly, forms an elevated head rest. With the back section horizontally disposed, and with the head section tilted downwardly 15° or thereabouts, the patient's head will drop downwardly with respect to the body and thus examination of certain portions of the patient's head is facilitated in this position.

Pivottally or rigidly connected within the frame section 10 aforesaid is a seat or thigh section 16 and pivotally connected as at 17 to the outer forward end thereof is a leg section 18 and the same may be positioned as shown in chair position (see Fig. 1) or may be horizontally disposed for bed formation depending upon patient positioning desired.

As shown in Fig. 3 the seat section 16 includes a central aperture 19 and associated therewith is a suitable receptacle for sanitary purposes, same herein serving as a receptacle, not shown, for drainage or waste from the sanitary device 40 presently to be described.

This sanitary device comprises a container 20, generally rectangular in outline, and having any number of compartments therein, the central one of which (21) has a depending outlet 22 (see Fig. 3) connected to a flexible waste 23. This flexible waste 23 normally is bent back and associated with the clip 24 carried by the underside of the sanitary device 20, as shown by the dotted lines. This sanitary device includes additional compartments such as the end compartments 25 for sanitary accessories and other paraphernalia. Each has an independent friction latching cover 26 hingedly connected as at 27 to sanitary device 20. The central cover may mount a mirror 28 upon its inner face. Each of the covers includes the rail portion 29 and when the compartments are covered the top of the container serves as a table, a reading or writing support, or the like.

For sanitary purposes (see dotted lines in Fig.

1) there is provided a hot water supply 38, a cold water supply 31, a mixing structure 32, a hot water control valve 33, a cold water control valve 34 and a flexible conduit 35. The latter terminates in a discharge nozzle 36 controlled by a hand valve 37. Thus hot water, cold water or warm water may be supplied the central compartment 21 when the hose 35 is extended and the nozzle 36 positioned in the central compartment. Obviously, a stopper for outlet 22 is provided.

Pivotedly supported at each side of the device 20 is a tubular arm 38 and the latter terminates in a rotatable element 39 carried by the angular and inwardly directed end of the tube 38. A lock screw 40 is adapted to engage the member 39 and lock the device thereto in the adjusted position.

The other end of each tube 38 terminates in a collar 41 with which is associated a clamping screw 42, the latter being arranged to clamp the tube 38 to rod 43, which is pivoted at 44 upon the back section 11 intermediate the ends thereof.

Rigid with the member 44 is the rearward extension 45 and extending inwardly towards each other are the arm portions 46 which are connected by the U-shaped portion 47 which extends transversely of the back section and maintains proper spacing of the arms for proper spacing thereof with respect to the sanitary device ends.

Each portion 46 includes another angular extension 48 and pivoted at 49 on the end thereof is a piston rod 50 which extends into cylinder 51. Cylinder 51 carries a piston 52 carried by the other end of the rod 50. Within the cylinder 51 and between the rod end thereof and the piston 52 and surrounding the rod 50 is a spring 53.

The other end of the cylinder 51 is pivotally supported as at 54 upon an arm 55 of an extension 56 secured to the upper or outer corner of the back section 11. The springs 53 normally constrain the pistons 52 to their position as shown in Fig. 1. Thus spring power is utilized for projecting the sanitary device forwardly and downwardly. This position is limited by fluid pressure release to the desired degree. When the proper position of the device has been attained pressure release is cut off and fluid is trapped in the upper end of the cylinder in the desired amount. It is to be understood that the two lines to the two cylinders (one to each cylinder) are controlled by common means so that pressure fluid is supplied to the cylinders and exhausted therefrom equally or the amounts trapped in each cylinder are equal.

When it is desired to elevate the device from the position shown in Fig. 1 to any position higher than that, up to and including the position shown in Fig. 2, pressure fluid is supplied to the head or upper end of the cylinders 51, the pistons are forced downward and the springs 53 are compressed. This tilts the two arms counter-clockwise (see Figs. 1 and 2) until the desired position of the sanitary device is attained, whereupon further pressure fluid supply is cut off and fluid pressure trapped therein.

Obviously, this action loads the springs 53 so that, upon release of the trapped pressure fluid, the springs become effective for device lowering or clockwise rotation to the extent permitted by fluid release.

It will be noted that the sanitary device may be adjusted at 41-42 away from its pivot 44 whenever desired or required, as when an extremely large patient is occupying the bed, then in the chair position.

Referring to Figs. 1 and 2 it will be noted that the central portion 44 of the arm structures carries a pin 59 and it will be observed in Fig. 4 that the same projects inwardly and that the portion 44 constitutes a cap that has in aligned relation the members 45 and 43 suitably secured thereto as at 45a and 43a. This cap arrangement mounts a central stud 60, the inner end of which is threaded as at 61. 11a designates a portion of the back section or more particularly the side frame portion thereof, the same being apertured at 62, concentric with the aperture, and projecting outwardly from this frame portion is the collar portion 63. This collar portion has an arcuate groove 64 therein, the ends 64a and 64b of which constitute stops for the pin 59 which rides in the arcuate groove 64.

A pair of lock nuts 65 suitably secure the arm structures in pivoted relation upon the frame portions 11a of the back section of the bed structure and the groove ends 64a and 64b limit the tilting of the arms so that in the event of excessive pressure application or failure of pressure application the sanitary device can not overtravel in either the clockwise or counter-clockwise directions.

When the drawing (see Fig. 2) is tilted 90° counter-clockwise it will be observed that the sanitary device is inverted with respect to its position shown in Fig. 1 and it serves as a head stop or head board for the resulting bed structure. Furthermore, in this position it is entirely out of the way so that the patient may be placed in the chair or get into it and out of it or, if bed parts are arranged in bed position, the patient may readily be transferred from a traveling cart or litter to the bed structure without interference from said sanitary device.

While the invention has been illustrated and described in great detail in the drawings and foregoing description, the same is to be considered as illustrative and not restrictive in character.

The invention claimed is:

1. In a chair type, multi-sectioned bed including a seat supporting frame having a width at least equal to the width of said bed and a length appreciably less than the over-all length of said bed, a seat section supported by the frame and having a width approximately equal to the width of said frame, and a back section pivoted at one end to said frame, the combination therewith of a head section pivoted upon the back section at the other end thereof and capable of being positioned at opposite sides of the general plane of said back section, a structure having a width approximately that of said seat section and being disposed transversely of said back section, and means at opposite sides of said back section and said structure for pivotally supporting said structure upon said back section, said structure being disposable in foot board relation to the back and head sections when aligned.

2. In a bed as defined by claim 1, power means for tilting said last mentioned means, and stop means limiting the extent of tilting movement of the structure.

3. In a chair type, multi-sectioned bed having a back section disposable in bed and chair back forming positions and a structure of approximately the width of said bed disposed transversely of said back section, the combination therewith of a pair of longitudinally extensible arms disposed at opposite sides of said

section and each being secured at one end to said structure, means pivotally mounting the other ends of said arms upon said back section intermediate the ends thereof, each of the last mentioned ends including an extension projecting beyond the pivotal axis of said ends, and U-shaped means connecting said extensions together.

4. In a bed as defined by claim 3, power means secured to the back section and connected to said extensions for power movement of the arms and the structure and stop means limiting tilting movement of said structure.

5. A bed as defined by claim 4 wherein the stop means and the arm pivotal mounting means are unitary. 15
